SAW-TOOTH WAVE GENERATOR

Max Geiger, Berlin, Germany, assignor to Telefunken Gesellschaft für Drahtlose Telegraphie m. b. H., Berlin, Germany, a corporation of Germany

Application July 24, 1937, Serial No. 155,456
In Germany July 27, 1936

3 Claims. (Cl. 250—36)

What has been called a "multivibrator" in the prior art of this nature is a saw-tooth wave generator in which there are two thermionic discharge paths the control grids of which through 5 a resistance-capacity mesh are driven or controlled by the plate circuit of the respective other thermionic discharge path. Relaxation or saw-tooth wave generators of this kind are particularly valuable for the production of impulse trains 10 of the sort required for instance, in television work. In their practical use, one fact that has often provided troublesome is that the duration or period of the generated impulses is a function of the value of the D-C potential supplied to the 15 saw-tooth wave generator as shall be explained more fully further below. In order to overcome this difficulty it is suggested according to the invention to excite by means of the current variations an oscillation circuit in one or in both of the 20 two thermionic discharge branches, the oscillations of said circuit to affect the behaviour of the other thermionic discharge branch, or of both discharge branches, as the case may be.

My invention will best be understood by reference to the drawings in which,

Fig. 1 is an embodiment of my invention,

Figs. 2, 2a, 2b, 2c, 3 and 4 are explanatory curves, and

Fig. 5 is a further embodiment of my invention.

By reference to Fig. 1 an exemplified embodiment is shown which generates impulses of practically constant duration. These impulses succeed one another at time intervals which are a function of the feed voltages of the multivibrator. The plate circuit of one of the discharge paths or tubes includes a choke coil which is in close coupling relationship with the choke coil of an oscillation circuit included in the grid lead of the other discharge path.

Referring to Fig. 1, 10 and 11 are two tubes. Tube 10 contains in its plate circuit a choke coil 12 and a resistance 13. The plate circuit of tube 11 contains only a resistance 14. The control grid lead of tube 10 includes a resistance-capacity mesh 15 through which the control grid, in a way customary with multivibrators, is united with the plate of tube 11, that is to say, through a condenser 16, while through a resistance 17 connection is established with the filament of tube 10. In the control grid lead of tube 11 is included an oscillatory circuit 18 comprising a choke coil 19 and a condenser 20. As to the rest, the grid circuit of tube 11 is also connected up in a way as known from the prior art of multi-

vibrators, that is to say, a condenser 21 is connected through lead 22 between the plate end of the resistance 13 and the oscillation circuit 18, and resistance 23 is in series with the said condenser 21. Resistance 23 has its lower end connected with a potential which is positive with respect to the filament of tube 11, that is, it is connected with tap P of the D. C. source of potential 24. The connection 25 indicated by broken lines between the upper terminal of condenser 21 and the lower terminal of the choke coil 12 shall be discussed further below.

Disregarding for the present choke coil 12, the oscillatory circuit 18 and the resistance-capacity mesh 15, the circuit organization shown in Fig. 1 represents a multivibrator which distinguishes itself from the conventional type of multivibrator known in the art in that the lower end of resistance 23 is positive in reference to the filament or cathode of tube 11. This particular step 20 embodied in the circuit arrangement which is designed to reduce the liability of disturbing actions in the multivibrator has been disclosed in my copending patent application Ser. No. 145,974 filed June 2, 1937. The resistance-capacity mesh 25 15 has the purpose of rendering the shape of the potential wave of tube 11 as rectangular as possible as described in my copending application Ser. No. 146,986 filed June 8, 1937. In the usual type of multivibrator, as is well known, the shape 30 of the potential of the two tubes is as shown by curves Figs. 2a and 2b, the former representing the grid potential of tube 10 and the latter that of tube 11. In both graphs, the horizontal coordinate stands for time, and from the line marked "O" which corresponds to the filament potential of the two tubes, the potential of the control grid is plotted downwards. In both graphs, the broken line K corresponds to the lower knee of the plate current-grid potential 35 35 characteristic of the tube. Both graphs show that the control grid potential of tube 11 during the time interval between t_1 and t_2 , and that of tube 10 during the time interval t_2 and t_3 rises slowly and that at instant t_2 the flow of current 40 in tube 10 is interrupted, while flow of current is initiated in tube 11; but that at instant t_3 the plate current of tube 11 disappears while the plate current in tube 10 resumes flowing. Owing 45 to the connection of the lower end of resistance 23 with the positive potential at point P, Fig. 2a is not altered at all, while Fig. 2b must be replaced by Fig. 2c in which the rise of grid potential has a horizontal line located above the zero line and marked "P" as its asymptote rather 50 55.

than line O as shown in Fig. 2b. The resistance-capacity mesh 15, as already pointed out, acts in the sense of producing a greater steepness of the rise of potential at the grid of tube 10 at the instant t_1 and t_3 . In Fig. 2a the rise of potential is shown perpendicular.

Now, across the choke coil 12, at instant t_1 a potential will arise in a sense as indicated in Fig. 1 by plus and minus signs. The close coupling 10 of coil 12 with coil 19 of the oscillation circuit 18 is chosen in such a way that there then is developed a potential across the coil 19 whose direction is indicated by plus and minus signs. This leads to the production of a half-cycle in 15 the oscillatory circuit 18, the shape of the potential being indicated by the sinuous alternation S, Fig. 3. The amplitude A of this voltage alternation is assumed to be high compared with the drive range of tube 11, in other words, great compared 20 with the vertical distance of lines O and K, Figs. 2b and 2c. Thus, at the grid of tube 11 the shape of the potential wave will first be as shown in Fig. 2c (which, as will be noted, corresponds to the potential of the lower terminal of condenser 25 21), and additionally the potential shown in Fig. 3. The total potential of the control grid, therefore, is the sum of the ordinates in Figs. 2c and 3. If only the alternation shown in Fig. 3 acted at the grid of tube 11, and if the drive range of 30 tube 11 were small compared with the amplitude A, the line K would be intersected practically where the sine passes through zero. This point of intersection would be independent of the value of the D-C potential 24 seeing that, while the 35 amplitude A is a function of the value of the working voltage, this is not true of the duration of the alternation. In practice, however, the constant location of t_2 still exists also when taking in consideration the grid voltage share 40 according to Fig. 2c inasmuch as the grid potential at time t_2 is far less steep than the sine curve S.

It thus follows that the shape of the grid potential of tube 11 comprises a component which, 45 as regards to the passage through zero is independent of the value of the D-C potential, and further a component which is a function of the value of the D-C potential, which latter, however, by choosing a convenient time constant for 50 21 and 23 may be so diminished that it is practically negligible. In other words, the time interval t_1 , t_2 , the length of the impulses arising at the plate of tube 11 is independent of the value of the D-C potential.

55 By reference to Fig. 4 it shall be shown that there is no such independence in the case of an ordinary multivibrator. Fig. 4 shows the shape of potential impressed on the grid of tube 11 in so far as the same is due only to the resistance-capacity mesh, that is, for two different potentials U_1 and U_2 of battery 24, U_1 being assumed to be higher than U_2 , the further assumption being made that the change of potential as far as instant t_2 is to proceed along the initial tangent. It will be seen that the line corresponding to U_1 cuts the straight line K later than the one corresponding to U_2 intersects said straight line. In other words, it will be noted that as a matter of fact the length of the impulses greatly 60 depends upon the voltage if the oscillation circuit of this invention is absent.

When the resultant potential of the control grid of tube 11 as shown in Figs. 2c and 3 cuts the line K, plate current starts to flow in the 65 tube 11. This plate current, for the reasons pre-

vailing in the case of a multivibrator, will always rise rather rapidly until grid current begins to flow. When this happens, parallel damping arises for the oscillation circuit 18, said damping consisting in the series arrangement of the grid-filament resistance of tube 11, the vanishingly low inner resistance of the lower end of battery 24 and the resistance 23. Resistance 23 may be chosen far smaller without occasioning any change in the time constant of 21 and 23, for 10 there is a chance to increase at will the value of the condenser 21 in a corresponding measure. By action of the parallel damping the second 15 alternation or half-cycle is strongly damped with the result that its amplitude will be far lower than magnitude A, and that thus the third alternation which has the same sign again as the first alternation S turns out to be comparatively small. The resistance 23 may be made so small that for the third alternation in Fig. 3 the plate current of tube 11 will still be of finite size.

However, if then the upper terminal of the condenser 21 through the connection 25 shown by the dotted line in Fig. 1 is united with the plate end of the choke coil 12, there results at the 25 grid of tube 11 not only the sinuous potential arising in the coil 19, but in addition the potential developed across the choke coil 12 which reaches the grid capacitively by way of 21.

An improvement in the operating conditions 30 of the multivibrator as shown in Fig. 1 is obtainable also for the reason that a pentode, that is a tube having a screen grid, is used rather than an ordinary tube. This makes it permissible to make the choke coil 12 much larger so 35 that a very large amplitude A, the arrangement producing the wave form of Fig. 4 may be used without the deleterious features of unsteadiness or discontinuance of the plate current in tube 10 producing undesirable results. 40

Referring to Fig. 5, there is shown an arrangement wherein an oscillatory circuit is provided in the grid circuit of both of the thermionic tubes. A multivibrator of this kind works in this manner that, after termination of the second alternation, Fig. 3, the tube 10 is started or ignited again, in other words, that impulses of like length are set up in both branches, the duration of which, for the reasons hereinbefore set forth, is independent of the potential. 50

Instead of including the resistances 13 and 14 and the choke-coil 12 in the plate circuit of discharge vessels, they could be connected also, for instance, in screen-grid circuits or, generally speaking, in circuits of current-carrying electrodes. 55

What I claim is:

1. An oscillation generator comprising a pair of thermionic discharge tubes having an anode, cathode and at least one control electrode, a 60 time constant circuit connected in the grid-cathode circuit of the first of said thermionic discharge tubes, a resistor connected in series with said time constant circuit, an inductive member connected in the anode-cathode circuit of said tube, resistive means connected in series with said inductive member, a condenser for coupling the grid of said first tube to the anode-cathode circuit of the second thermionic discharge tube, a resonant circuit connected in the grid-cathode 65 circuit of the second thermionic discharge tube, said resonant circuit being variably coupled to the inductive member connected in the anode-cathode path of said first tube, a resistor connected in series with said resonant circuit, means 70

for energizing the anodes of said tubes, a connection between the last named resistor and a point on said supply having a positive potential with respect to the cathode of the second tube,
5 means coupling the grid of the second tube to the anode of the first tube, and a resistor connected in the anode-cathode circuit of the second thermionic discharge tube.
2. An oscillation generator comprising a pair of thermionic discharge tubes having anode, cathode and at least one control electrode, a resonant circuit connected in the grid-cathode circuit of the first of said thermionic discharge tubes, a resistor connected in series with said 10 resonant circuit, an inductive member connected in the anode-cathode circuit of said tube, resistive means connected in series with said inductive member, a condenser for coupling the grid of said first tube to the anode-cathode circuit of the second thermionic discharge tube, a resonant circuit connected in the grid-cathode circuit of the second thermionic discharge tube, said resonant circuit being variably coupled to the inductive member connected in the anode-cathode path of said first tube, a resistor connected in series with said resonant circuit, means for energizing the anodes of said tubes, a connection between the last named resistor and a point on said supply having a positive potential with respect to the cathode of the second tube,
15 20 25 30

means coupling the grid of the second tube to the anode of the first tube, and a resistor connected in the anode-cathode circuit of the second thermionic discharge tube.

3. An oscillation generator comprising a pair of thermionic discharge tubes having anode, cathode and at least one control electrode, a resonant circuit connected in the grid-cathode circuit of the first of said thermionic discharge tubes, a resistor connected in series with said resonant circuit, an inductive member connected in the anode-cathode circuit of said tube, resistive means connected in series with said inductive member, a condenser for coupling the grid of said first tube to the anode-cathode circuit of the second thermionic discharge tube, a resonant circuit connected in the grid-cathode circuit of the second thermionic discharge tube, a resistor connected in series with said resonant circuit, means for energizing the anodes of said tubes, a connection between the last named resistive and a point on said supply having a positive potential with respect to the cathode of the second tube, means coupling the grid of the second tube to the anode of the first tube, a resistor connected in the anode-cathode circuit of the second thermionic discharge tube, and an inductive member connected in the anode-cathode circuit of the second tube.

MAX GEIGER. 30
